Primary Examiner — Justin M Jonaitis*Assistant Examiner* — Samantha K Pollack(74) *Attorney, Agent, or Firm* — Knobbe Martens Olson & Bear LLP(57) **CLAIM**

The ornamental design for a spa as shown and described.

DESCRIPTION

FIG. 1 is a front, top, and left side perspective view of a spa.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a rear, bottom, and right side perspective view thereof.

The broken lines in the drawings illustrate portions of the spa that form not part of the claimed design.

1 Claim, 6 Drawing Sheets(56)
